(57) **CLAIM**

The ornamental design for a collapsible cup carrier, as shown and described.

DESCRIPTION

FIG. 1 is a front view of a collapsible cup carrier showing my new design;

FIG. 2 is a side view of the collapsible cup carrier;

FIG. 3 is a perspective view from one side and above of the collapsible cup carrier; and,

FIG. 4 is a plan view of the collapsible cup carrier in a collapsed state.

The broken lines shown represent unclaimed subject matter and form no part of the claimed design.
